UNITED STATES PATENT OFFICE.

GEORGE SMITH, OF BALTIMORE, MARYLAND, ASSIGNOR TO ELLICOTT MACHINE CORPORATION, OF BALTIMORE, MARYLAND, A CORPORATION OF DELAWARE.

DREDGING APPARATUS.

Application filed July 24, 1923. Serial No. 653,465.

To all whom it may concern:

Be it known that GEORGE SMITH, a citizen of the United States, residing at Baltimore, in the State of Maryland, has invented certain new and useful Improvements in Dredging Apparatus, of which the following is a specification.

This invention relates to an improved dredging apparatus and is more particularly directed to an improved construction of ladder for carrying the cutter-head, suction pipe and the driving mechanism for the cutter.

The object of the invention is to provide an improved and novel construction of means for pivotally mounting the ladder, and leading the suction pipe through one of the pivot mountings and to also provide improved means for sustaining the gearing with respect to the latter.

The invention is illustrated in the accompanying drawings, wherein,

Fig. 1. shows the improved mechanism in top view.

Fig. 2. illustrates the same in side elevation.

Fig. 3. shows the pivoted end of the ladder and the driving mechanism for the cutter-shaft on an enlarged scale and in top view.

Fig. 4. illustrates the same in side elevation.

Fig. 5. shows another side view of the ladder-pivot and the suction-pipe leading therefrom.

Fig. 6. illustrates the pivot-end of one of the ladder-arms as the same would appear if viewed on the line 6—6 of Fig. 3.

Fig. 7. shows a vertical sectional detail through one trunnion-end of the ladder and suction-tube, and the bearing for the same,—the section being taken on the line 7—7 of Fig. 3 looking in the direction of the darts.

Fig. 8. illustrates a vertical sectional detail through the other trunnion-end of the ladder and the bearing for the same, as the same would appear if viewed on the line 8—8 of Fig. 3, and

Fig. 9. shows in side view one of the bearing-supporting beams carried by the ladder as the same would appear if viewed on the line 9—9 of Fig. 3.

Referring to the drawings the numeral

12, designates the deck of a scow to the 55 edge of which there are secured two spaced-apart brackets 13 and 14.

Each bracket is provided with the lower half of a bearing 15, while the upper half 16 of each bearing is designed to be bolted 60 to the lower half in a well-known manner.

The bearings 15—16 of each bracket 13 and 14 are designed to pivotally sustain the inner end of the ladder 17. This ladder is formed of structural steel, including the 65 side beams 18 and 19 and the cross-beams 20 and braces 21. The side beams 18—19 converge as they extend away from the scow as readily seen in Fig. 1 of the drawings.

The side beam 18 of the ladder carries a bracket-plate 22 at its inner end which plate has a circular bearing-head 23. This head is provided on its outer side with a sleeve 24, as shown in Fig. 7 of the drawings, which sleeve fits in the bearings 15—16 and may be rotated therein. The interior of the sleeve 24 is of a larger diameter at 75 than the interior of the bearing-head 23 and a suction-pipe 26 has its end passing through the head and sleeve and carries an enlargement 27 which has bearing 80 in the sleeve.

It will thus be understood that the enlargement 27 of pipe 26 is held in the sleeve 85 24 of the head 23 and that the pipe, sleeve and head are all thus rigid with the bracket-plate 22 and may be rotated in the bearings 15—16 of bracket 13.

In view of the fact that the end of pipe 90 26 must rotate whenever the ladder 17, is swung, as will presently be more clearly understood, provision is made to connect a rigid elbow 28 thereto by means of a gland 29 and packing 30.

The suction pipe 26 extends forwardly along the ladder 17 from the bearing-head 23 and terminates at the forward end of said ladder adjacent to a cutter-head or equivalent device, shown at 31.

The side beam 19 of the ladder carries a bracket-plate 32 at its inner end which plate is provided with a circular head 33 whose exterior circumference fits into the bearings 15 and 16 of bearing-bracket 14.

The head 33 to all intents and purposes is the equivalent of a trunnion on the inner end of the ladder beam 19 because it fits

into the bearings 15—16 of the bracket 14 and will rotate therein as the outer end of the ladder is raised or lowered,—the sleeve 24 on the head 23 at the opposite side of the ladder serving as the trunnion at said latter side, and the suction pipe 26 passing through this latter trunnion.

In practice, a cable (not shown) is attached to the eye 34, (shown in Fig. 2) at the outer end of the ladder and by this means said outer ladder-end is raised or lowered while the inner pivoted end of the ladder will turn in the bearing-brackets 13 and 14 on the end of the scow.

Obviously, means must be provided to drive the cutter-head 31 at the outer end of the ladder and this means must be such as to permit the raising and lowering of the cutter-end of the ladder.

The cutter-head is carried at the outer end of a longitudinal shaft 35 which extends from one end to the other of said ladder and is mounted in bearings 36 on the ladder.

The inner end of the shaft 35 carries a bevel gear 37 which latter, in the present instance, is located centrally between the trunnion-ends of the ladder as clearly shown in Figs. 1 and 3 of the drawings.

From the ladder structure there are supported two spaced-apart bearings 38 and 39 respectively. The bearing 38 is carried on the end of a beam 40 at the inner end of the ladder, as best seen in Figs. 3 and 9 of the drawings, while the bearing 39 is supported by a bracket 41 that projects from the inner side of the trunnion-head 33, as shown in Figs. 6 and 8 of the drawings.

Obviously, as the two bearings 38 and 39 are carried by structures that are attached to the ladder, said bearings will swing as the ladder turns on its trunnions.

A horizontal shaft 42, is sustained by the ladder-bearings with its axis in alignment with the axis of the trunnions, and this shaft 42 carries a pinion 43 at its inner end which meshes with the bevel gear 37.

Between the two ladder-bearings 38 and 39 the shaft 42 carries a gear 44 which meshes with and is driven by a pinion 45, that is carried on one end of a driving-shaft 46 which is carried in a suitable bracket 47 mounted rigidly on the scow.

The other end of shaft 46 carries a large gear 48 which is driven by a pinion 49 on the shaft of a motor 50.

From the foregoing explanation it is to be understood that the driving mechanism including the motor 50, pinion 49, gear 48 and pinion 45, is carried on the scow while the driven mechanism, including the gear 44, shaft 42, pinion 43, gear 37 and longitudinal shaft 35 is carried on and moves with the ladder.

Thus the ladder may be swung on its trunnions to a raised or lowered position

without disconnecting any of the gears,—the gear 44 simply moving around the circumference of the pinion 45, which drives it during such swinging movement.

Having described my invention, I claim,—

1. In a dredging apparatus carried by a scow, the combination of a pair of spaced bracket members secured to and projecting from the scow, a ladder structure, a pair of bracket plates secured to one end of the ladder, sleeves projecting from said bracket plates rotatably mounted in said bracket members, a suction pipe carried by said ladder having an end extending through one of said sleeves, and a stationary elbow into which the end of said suction pipe projecting through said sleeve extends.

2. In a dredging apparatus carried by a scow, the combination of a pair of spaced bracket members secured to the scow, bearings supported by said bracket members, a ladder structure, a pair of bracket plates secured to said ladder, sleeves carried by said bracket plates pivotally mounted within said bearings, a suction pipe carried by said ladder having an end projecting through one of said sleeves, and an elbow secured to said scow into which the projecting end of said suction pipe is rotatably associated.

3. In a dredging apparatus carried by a scow, the combination of bearing bracket members secured to one end of said scow in spaced relation, a ladder device, a pair of spaced bracket plates secured to the inner end of said ladder device, said bracket plates being formed with a bearing head having a sleeve extending axially thereof, said sleeves being rotatably mounted in said bearing bracket members, a suction pipe secured to said ladder having an end mounted through and projecting from one of said sleeves, and a stationary elbow with which the projecting end of said suction pipe is rotatably associated to provide a swiveling leak proof joint.

4. In a dredging apparatus carried by a scow, the combination of spaced bearing brackets secured to one end of the scow, a ladder frame, plates secured to the inner ends of the sides of said ladder frame, a bearing head extending from each plate, a sleeve extending from each of said heads pivotally carried by said bearing brackets, one of said heads and the adjacent sleeve having coaxial bores of different diameters extending therethrough transversely to the sides of said ladder frame, a suction pipe carried by said ladder frame having its inner end extending through the bores of said bearing head and the adjacent sleeve, said pipe end being formed to conform to the diameters of the bores in said bearing head and sleeve to prevent lateral inward displacement thereof, and a stationary elbow

on said scow with which the projecting end of said pipe is associated in leak proof relation.

5. In a dredging apparatus carried by a scow, the combination of a ladder frame, bearing plates secured to the inner end of said ladder, a bearing bracket carried by one of said plates bearing members on said scow with which said bearing plates are hinged, a cutter head carried by said ladder frame, a shaft for rotating said cutter carried by said frame, power transmission mechanism

15
20

connected to said shaft, a bearing bracket secured to said ladder frame adjacent said bearing bracket carried by one of said bearing plates, said bearing brackets supporting said transmission mechanism, and a source of power on said scow, said transmission mechanism being connected with said source of power to be driven thereby in any position in which said ladder frame may be pivotally moved.

In testimony whereof I affix my signature.
GEORGE SMITH.
